UNITED STATES PATENT OFFICE.

IVAN J. NELSON, OF SAGINAW, MICHIGAN.

WINDSHIELD WIPER.

Application filed April 5, 1922. Serial No. 549,796.

To all whom it may concern:

Be it known that I, IVAN J. NELSON, a citizen of the United States, residing at Saginaw, in the county of Saginaw and State 5 of Michigan, have invented certain new and useful Improvements in Windshield Wipers; and I do hereby declare the following to be a full, clear, and exact description of the invention, such as will enable others 10 skilled in the art to which it appertains to make and use the same.

This invention relates to wind shield cleaners for motor vehicles and the like and pertains more particularly to that class of 15 wind shield cleaners in which a vertical wiper blade is made to travel across the wind shield from side to side, wiping the surface of the glass at each passage.

My invention pertains more particularly 20 to certain improvements in the construction and mode of operation of a wind shield wiper of the class described, whereby the objects of my invention are attained.

These objects are, first, to provide a wind 25 shield cleaner in which the wiper blade during its travel is yieldingly pressed against the surface of the glass, the desired pressure being obtained by a roller or equivalent device co-acting with the top rail of the wind shield sash and located on the same side of 30 the glass as the wiper.

A still further object is to provide in combination with the top rail and side rails of 35 the wind shield sash a driving mechanism carried by the sash, but so arranged with respect to the sash as to permit the sash to be tilted without interfering with the stationary frame in which the tilting sash is mounted.

With the foregoing and certain other objects in view which will appear later in the specification, my invention comprises the devices described and claimed and the equivalents thereof.

In the drawings, Fig. 1 is a front view, 45 broken away in part, showing a tiltable wind shield with my improvement attached.

Fig. 2 is a vertical section on the line 2-2 of Fig. 1.

Fig. 3 is a top plan view of the working 50 parts shown in Fig. 1, the sash and frame removed.

Fig. 4 is a perspective view of the travelling pin that engages the screw shaft by which the wiper is propelled.

As is clearly shown in the drawings, 55 1 indicates the usual glass pane of a wind

shield. 2 indicates a vertical side rail of the sash and 3 the top rail. 4 shows the frame of the machine upon which the tiltable sash is mounted. Upon the top rail 3 and outside the vision of the glass 1 is mounted a screw shaft 5, preferably formed with a right-hand and a left-hand thread.

The screw shaft is mounted in suitable bearings, as 6 and 7, secured to the rail 3, 60 and the screw is driven by a gear 8 or its equivalent on the end of the shaft. In mesh with the gear 8 is a pinion 9, which may be integral with a worm wheel 10 meshing with a worm 11 on the shaft of a suitable motor 70 12.

Referring to Fig. 2, it will be seen that the top rail 3 of the sash is formed with a longitudinal groove 13 along one side and that the screw 5 lies within this groove and 75 practically flush with the face of the rail 3.

On the shaft 5 is a traveling nut 14, within which is a pin 15, shown in perspective in Fig. 4, the lower reduced end of this pin engaging and traveling in the thread of the 80 screw 5, so that while the screw is revolving continuously in one direction the nut 14 will travel from end to end of the screw, automatically reversing its movement at each extremity of its travel. For purposes 85 of illustration I have shown the screw thread as extending only part of the length of the shaft.

16 is a vertically disposed bar, preferably 80 of spring metal and slightly bowed at its lower part. It is fixed to the traveling nut 14 and upon its upper end above the nut 14 is mounted an idle roller 17 preferably of soft rubber or other suitable material. This 90 roller, carried by the nut, travels along the upper outer face of the top rail 3, and while so traveling presses the wiper blade 18 snugly against the glass 1, as shown in Fig. 2.

Since wind shields of the class described 100 are usually tiltable with respect to the frame 4 of the dash, I prefer to so construct the corner of the wind shield upon which the shaft-driving mechanism is mounted that the gears or other devices comprising the driving mechanism will be compactly housed 105 without interfering either with the vision or with the tilting of the wind shield sash.

A preferred form of my wiper driving arrangement is shown in Fig. 1, where 19 is an offset in the rail 2 of the wind shield 110 sash, permitting the gears 8, 9 and 10 to be mounted upon the end of the top rail 3.

without projecting laterally beyond the edge of the upright rail 2, and consequently without interfering with the frame 4 when the sash is tilted.

5 By means of the above described invention I have produced a simple, compact and strong, yet relatively inexpensive wind shield wiper, the parts of which are so located as to be inconspicuous.

10 The arrangement of my improved wiper is such that the roller 17 may be mounted upon the same side of the wind shield as the wiper 18, so that no part of the wiping mechanism need be extended from the rear

15 side around to the front or weather side of the wind shield glass.

While I have shown and described a drive including a direct connected motor, the motor being mounted on the top rail of the 20 sash, yet it will be obvious that any other form of drive, as a flexible shaft or a chain, might be substituted for the direct connected motor drive, without departing from the spirit of my invention as set forth in the 25 claims.

Having thus described my invention, what

I claim and desire to secure by Letters Patent is:

1. In combination, a wind shield sash having a longitudinal groove in one rail thereof, a revolvable screw shaft within said groove, a corner of said sash being formed with an offset providing a recess, gears connected to said shaft and located in said recess, a traveling nut on said revolvable screw shaft, a spring-pressed wiper carried by said nut, a roller carried by said nut opposite said wiper, said roller traveling upon the outer face of the rail of said sash for the purposes set forth. 30

2. In combination, a wind shield sash having a longitudinal groove in one rail thereof, a revolvable screw shaft, a traveling nut on said shaft, a spring-pressed wiper carried by said nut, a roller carried by said nut and located on the side of said nut opposite said wiper, said roller traveling upon the outer face of said sash. 35

40 In testimony whereof, I affix my signature.

IVAN J. NELSON.
